F. M. WILLIAMS.
PROTECTING DEVICE FOR VESSELS.
APPLICATION FILED JUNE 23, 1917.

Patented Mar. 26, 1918.

Inventor

By Watson E. Coleman

Attorney

UNITED STATES PATENT OFFICE.

FRANKLIN M. WILLIAMS, OF WINNEMUCCA, NEVADA.

PROTECTING DEVICE FOR VESSELS.

1,260,496.

Specification of Letters Patent. Patented Mar. 26, 1918.

Application filed June 23, 1917. Serial No. 176,608.

To all whom it may concern:

Be it known that I, FRANKLIN M. WILLIAMS, a citizen of the United States, residing at Winnemucca, in the county of Humboldt and State of Nevada, have invented certain new and useful Improvements in Protecting Devices for Vessels, of which the following is a specification, reference being had to the accompanying drawings.

10 This invention relates to a protecting device for vessels and has for its primary object to provide very simple and effective means for protecting a vessel against torpedo attacks by submarines, and which includes a longitudinally extending guard plate to ward off the torpedo or cause its explosion before striking the hull of the vessel.

15 It is another object of the invention to provide improved means for lowering or raising the longitudinally extending guard plate to an operative or inoperative position.

20 It is also another object of the invention to provide an improved construction of guard plate so that the same will effectively 25 ward off or explode a torpedo striking adjacent to the edges thereof.

It is a further general object of the invention to provide a device for the above purpose, which is strong and durable in its construction, may be operated with facility, and can be manufactured and applied to the vessel at relatively small cost.

25 With the above and other objects in view, my invention consists in the novel features 30 of construction, combination, and arrangement of parts to be hereinafter more fully described, claimed, and illustrated in the accompanying drawings, in which:

Figure 1 is a side elevation illustrating 40 one embodiment of my improved guard device;

Fig. 2 is a top plan view;

Fig. 3 is a section taken on the line 3—3 of Fig. 2; and

45 Fig. 4 is an enlarged vertical section through the guard plate.

Referring in detail to the drawing, 5 designates a cable extending longitudinally along each side of the vessel and around the 50 ends of the vessel's hull. The end portions of this wire extend beneath the stern end of the vessel's deck in intersecting relation and are suitably secured to rails or other fixed parts on the deck of the vessel. This wire 55 is attached to a series of spaced bracket plates 7 which are arranged upon each side

of the vessel's hull, said plates each being provided with spaced ears 8 between which the horizontally swinging davits 9 are pivotally mounted at their inner ends. The davit 60 at the forward end of the vessel is adapted to be detached from the bracket plate, a removable pin or key 10 being provided for this purpose.

11 designates the guard plate preferably 65 constructed of multiple ply sheet metal securely riveted together. This plate is provided upon its lower longitudinal edge with a longitudinal rib or reinforcement indicated at 12, and the forward end of said plate 70 is obliquely inclined upwardly and forwardly from the lower edge to the top edge thereof. This forward edge of the plate is also provided with a reinforcing flange or rib 13 on its outer side. This reinforcing 75 forward end of the plate is outwardly bent or flared away from the side of the vessel, as clearly indicated in Fig. 2 of the drawing. To this forward end of the plate, at its lower edge, one end of a cable 15 is connected, said cable extending around the prow 80 of the vessel and being attached at its other end to a suitable windlass 16 mounted upon the deck thereof.

Upon the free end of each of the davits 85 9, the pulleys 17 and 18 are mounted, said pulleys being respectively arranged below and above the davit. Cables 19 extend around the pulleys 17 and are suitably attached to the upper edge of the guard plate 90 11, the other ends of said cables being connected to the drums 20 mounted upon the deck of the vessel. Cables 21 also extend around the other pulleys 18 and are connected to the davits, said cables being wound 95 upon drums 22. The free ends of the davits are connected together by a flexible wire or cable 23, said cable extending from the rear davit around the stern of the vessel and being secured to suitable means on the far side 100 of the vessel's deck. A cable 24 is also connected to the free end of the forward davit 9 and extends around the bow of the vessel and is suitably secured at its other end to a stationary part on the deck at the opposite 105 side of the vessel. To the inner end of this davit which is detachably connected to the bracket member 7, one end of a wire or cable 25 is attached, the other end thereof being suitably fastened to means on the forward 110 end of the deck.

From the foregoing description, taken

in connection with the accompanying drawing, the construction, manner of operation and several advantages of the invention will be clearly and fully understood. When 5 the guard plate is to be swung inwardly along the side of the vessel to an inoperative position, the vessel is stopped and the cables 15 and 24 are slackened. The pin 10 is then removed and the forward davit 9 10 disconnected from the bracket member 7. The cables 21 are now wound upon their respective drums so as to swing the several davits laterally in a rearward direction, thereby drawing the guard plate in along 15 the side of the vessel's hull. By now winding the cables 19 upon their drums, the guard plate may be raised out of the water. The forward davit 9 which has been detached from the bracket, is fastened by 20 means of the cable 25 to the anchoring means on the deck of the vessel. Preferably, a small line or cable, indicated at 27, is connected to the main supporting cable 5 at the bow of the vessel, and fixed to 25 means on the deck thereof. By mounting the cable 5 in the manner described, it may be raised or lowered by means of this supporting cable 27 in accordance with the draft of the vessel when it is loaded or 30 empty. The protecting plate is swung out to its operative position by first winding up the cables 15 and 24 and then slackening the cables 21 so as to permit the davits to swing outwardly. The forward davit is re- 35 leased from its position along side of the vessel and is connected to the forward bracket plate 7. The cables 19 are then released so that the guard plate will lower by gravity to the desired depth in the water. 40 From the above it will be seen that I have devised a very simple and effective attachment for vessels, whereby they may be protected against torpedo attacks by submarines and the destruction of the vessel pre- 45 vented. It will, of course, be understood that any desired number of the davits 9 may be employed and the guard plate may

be made of any required length. Suitable mechanism will, of course, be provided for operating the several winding drums in unison, but as such drum operating mechanism provides no part of the present invention, it has not been herein described in detail. 50

While I have above referred to one construction of my invention whereby the desired ends may be satisfactorily attained, it is, of course, to be understood that the form, construction, and relative arrangement of the several parts employed is susceptible of considerable modification and I, therefore, 60 reserve the privilege of adopting all such legitimate changes as may be fairly embodied within the spirit and scope of the invention as claimed. 65

Having thus fully described my invention, what I desire to claim and secure by Letters Patent is:

A guard device for vessels including a cable extending around the hull of the vessel, spaced brackets secured to said cable, 70 davits mounted at one of their ends in certain of the brackets for horizontal swinging movement, an additional davit detachably mounted at one of its ends in the forward bracket, a guard plate, means for adjustably suspending said plate from the free ends of 75 the davit, said forward davit extending at an angle with respect to the first named davit when the guard plate is disposed in its operative position in spaced relation to 80 the side of the vessel, a flexible connection between the free ends of all of the davits, and means for operating the first named davits when said forward davit is disconnected from its bracket to move the guard 85 plate inwardly in close proximity to the hull of the vessel.

In testimony whereof I hereunto affix my signature in the presence of two witnesses.

FRANKLIN M. WILLIAMS.
